FASTENING DEVICE

Herman Kluger, New York, N. Y., assignor to
Fulford Mfg. Co., a corporation of Rhode
Island

Application July 12, 1933. Serial No. 680,066

1 Claim. (Cl. 24—213)

This invention relates to a stud for a snap fastener and has for one of its objects the provision of a less expensive structure by requiring a minimum number of parts and yet one which will be strong and durable for the purposes for which it is intended.

Another object of the invention is the provision of a structure which will form the stud and its securing means as one unit with all of the parts necessary for assembly of the stud on a garment and without the necessity of handling two separate parts for attachment to the garment.

Another object of the invention is the provision of a structure which when assembled on the garment will comprise one less piece than has heretofore been necessary and yet secure such stud on the garment in a secure and durable manner.

Another object of the invention is the provision of a stud for a snap fastener which will eliminate the requirement of a hole first punched in the fabric in order that it may be assembled thereon but which will carry protruding prongs which can be forced through the fabric and doubled over and thus simplify the operations necessary in securing the stud on the fabric and speed up the assembly of studs on garments or to other parts upon which it is desired that they be secured.

A still further object of the invention is the provision of a finding for a stud which will enable these advantageous results to be performed and yet which is one which may be made of a single piece of metal or the like.

With these and other objects in view, the invention consists of certain novel features of construction, as will be more fully described, and particularly pointed out in the appended claim.

In the accompanying drawing:

Fig. 1 is a perspective view of the stud as secured onto a piece of leather or fabric upon which it is desired that the same be mounted.

Fig. 2 is a back plan view of this stud as mounted on the fabric.

Fig. 3 is a perspective view of the cage member or stud proper of the device.

Fig. 4 is a perspective view of the body member of the device.

Fig. 5 is a sectional view showing the cage and body members assembled.

Fig. 6 is a perspective view of the securing member.

Fig. 7 is a sectional view showing the parts as

illustrated in Figs. 5 and 6 in assembled relation.

Fig. 8 is a top plan view of the blank from which the securing member is formed.

Figs. 9, 10, 11 and 12 are sectional views showing progressive steps in the shaping of the blank shown in Fig. 8 into the securing member illustrated in perspective in Fig. 6.

It has been usual in the securing of studs for snap fasteners to garments or other parts upon which this part of the snap fastener is mounted to provide a body member, a cage or resilient projection, an anvil member within this cage, and a separate post with an enlarged head which

was placed through a hole in the garment and forced against an anvil to cause its edges to be turned and secure the stud in the desired mounted position, thus requiring the punching of the hole in the garment or fabric and the separate

handling of the post with its enlarged head; and in order that a simplification of these operations may be had, I have provided a single piece which takes the place of the anvil and post with its enlarged head and which eliminates the necessity of providing a hole in the garment by

reason of the same having prongs whereby all of the parts are assembled in a single unit with no necessity of detaching any of the parts or assembling any of them to secure the fastener in position; and the following is a detailed description of the present embodiment of this invention illustrating the preferred means by

which these advantageous results may be accomplished.

With reference to the drawing, I have designated at 15 a piece of material such as leather, fabric or part of a garment upon which it is desired that a stud or a snap fastener be mounted. This snap fastener comprises a body

member, 16, shown in perspective in Fig. 4, as consisting of a flat plate, 17, of circular formation with a central opening, 18, therein while a flange, 19, extends downwardly from the peripheral edge of this plate 17.

The cage member designated generally, 20, consists of a drawn up portion of a sphere, 21, with a plurality of fingers, 22, extending downwardly and at the same time bulging outwardly, as at 23, to form a skeleton of a dome and permit of some resilience or compression of these

fingers in a usual manner for securing the snap fastener to a socket or the like. These fingers, 22, are each extended through an opening, 18, and are turned outwardly, as at 24, to lie along

105

110

the under or inner surface of the plate, 17, of the body member.

The securing member, which I will designate generally 25 and which is illustrated in Fig. 6, 5 is formed from a blank, 26, of generally circular formation with prongs, 27, protruding outwardly therefrom. Through a series of drawing operations, this blank is cupped, as illustrated in Fig. 9, with a drawn-up projection, 28, and flange, 29. 10 This projection, 28, is further drawn up into its finished form, 30, as illustrated in Fig. 10, in another operation after which the flange, 29, is bent inwardly together with the prongs as at 31 in Fig. 11, and finally this flange, 29, becomes an 15 inwardly-extending portion, 32, doubled back upon the plate, 33, with the prongs, 27, extending outwardly at right angles to the plate, 33, and doubled back portion, 32.

The securing member, as thus formed, is positioned within the flange, 19, of the body, 16, 20 while its projection, 30, substantially fits within the fingers, 22, to maintain them against the edge of the opening, 18, while the plate, 33, of my securing member holds the outwardly turned 25 ends of these fingers firmly against the under surface of the plate 17, by being forced thereagainst by the inward rolling of the edge, 35, of the flange 19. The prongs, 27, extend from the opposite side of the body of the device from that 30 from which the skeleton dome projects and are located inwardly from the periphery thereof allowing a marginal portion over which the rolled edge, 35, may extend.

These prongs, 27, are sharp and pointed as at 35 36 at their ends and may be forced through a piece of fabric, such as 15, making their entry without the fabric having been previously perforated, after which they may be rolled outwardly, as at 37, see Fig. 2, while the points, 36, 40

may extend upwardly again if desired to clinch the parts in the fabric.

The foregoing description is directed solely towards the construction illustrated, but I desire it to be understood that I reserve the privilege of resorting to all the mechanical changes to which the device is susceptible, the invention being defined and limited only by the terms of the appended claim. 80

I claim:

A stud for a snap fastener comprising a body member having a flat circular plate with an opening in its center, a wall extending downwardly from the outer edge of the plate, a cage member having a plurality of resilient fingers, 90 each bowed outwardly and forming a skeleton dome on the upper side of the plate of said body member, said fingers each extending through the opening in the plate and having portions contacting with the edges of the opening and the 95 free end portions extending outwardly to lie along the under surface of the plate and parallel thereto and a securing member comprising a plate closely fitted within the wall of the body member and provided with a drawn-up projection extending between the fingers of said cage member and contacting the inner surfaces thereof to hold them against the edge of said opening, the outer edge of the plate of said securing member being doubled back upon itself with 100 prongs protruding downwardly from the free edge of the doubled back portion, the wall of said body member having its edge extending inwardly over the under side of the plate of said securing member to hold the same tightly 110 against the outwardly extending ends of the fingers of said cage member and bind all of said members together. 105
